UNITED STATES PATENT OFFICE.

HENRY C. MILLER, OF WATERFORD, NEW YORK.

BUTTONHOLE MACHINE.

Application filed August 2, 1918. Serial No. 248,029.

To all whom it may concern:

Be it known that I, HENRY C. MILLER, citizen of the United States of America, residing at Waterford, in the county of 5 Saratoga and State of New York, have invented certain new and useful Improvements in Buttonhole Machines, of which the following is a specification.

This invention relates to improvements in 10 button hole machines.

One of the objects of the invention is to provide safety mechanism under control of the thread to prevent operation of the cutting blade if the stitches are not properly 15 formed, or should either the upper or lower thread break or give out.

Another object of the invention is to provide means under control of the upper thread to prevent the usual manual raising 20 of the clamp should the stitches be improperly formed, or should the thread pay out or become broken.

A further object of the invention is to provide in addition to the usual primary 25 automatic release of the stop motion after the stitching mechanism has performed its cycle of operation, a secondary trip or release, to insure of the usual cam which operates the cutting blade imparting the nec-

30 essary movement to positively act to drive the cutting blade down the requisite distance to form a perfect cut, and to permit return of the cutting blade to its proper normal position. This trip is so arranged and timed,

35 that the stop motion is tripped and is free to be disconnected from the power means at a predetermined point in the revolution of the cam every time the machine is operated. Although the delicate primary releasing 40 mechanism will be tripped, the cam will not be released from the power means until the secondary releasing means is reached, whereby the cutter blade is sure of being reciprocated its full stroke, which effectually prevents 45 breaking or bending the blade by devices subsequently operated in the complete cycle of operation of the machine.

Another object of the invention is the provision of means for gradually shifting the 50 needle bar to form the end barring stitches,

in lieu of suddenly throwing the parts to shift from the throw when making the side stitches, to the throw equal to the full width of the end barring stitches. The gradual shifting of the needle bar, together with the 55 usual width of vibratory movement produces end bars formed of a series of short stitches, each a trifle longer than the preceding one, and a series of long stitches equal in length to the full width of the bar, laid over 60 the shorter stitches.

The purpose of this gradual movement is to prevent bending or breaking of the needle, if per chance the delicate adjustments of the various parts are not accurate, or through 65 wear the timing is incorrect. If either or both conditions, are present, the fabric will drag the needle and bend or break it. By my improvement if this condition should be present, the short distance the needle is 70 dragged will not bend or break it.

I have discovered that the increment of movement of a piece of fabric between stitches used in forming button holes is so slight, it is not necessary to employ a step by 75 step feed motion, and therefore one of the objects of this invention is to provide means for continuously feeding the fabric during the stitching operation.

The invention also aims to improve the 80 construction and arrangement of the clutch and the cooperating mechanism to obviate the necessity of nicety of adjustment of parts, and to insure of the clutch working at the proper time in the cycle of operation 85 of the machine in case of wear.

In addition to the foregoing objects, my present invention comprehends improvements in the details of construction and arrangement of parts to increase the efficiency 90 of the machine as a whole, all of which will be hereinafter described and particularly pointed out in the claims.

In the accompanying drawings:—

Fig. 1 is a perspective view of my im- 95 proved machine.

Fig. 2 is a side elevation.

Fig. 3 is a view from the opposite side of the machine.

Fig. 4 is a bottom plan view, parts being 100

omitted to illustrate the connections employed to operate the improvements.

Fig. 5 is a diagrammatic plan view.

Fig. 6 is a plan view of the thread tension means.

Fig. 7 is a diagrammatic section on the line 7—7, of Fig. 2.

Fig. 8 is a detail perspective view of the clutch mechanism.

Fig. 9 is a detail perspective view of the thread tension controlling mechanism.

Fig. 10 is a detail end view of the stop motion device.

Fig. 11 is a detail perspective view of same.

Fig. 12 is a detail side elevation of the secondary tripping mechanism.

Fig. 13 is a detail view of the latch.

Fig. 14 is a diagrammatic elevation of the secondary releasing device, the parts being in operative position.

Fig. 15 is a similar view, the parts being in normal position.

Fig. 16 is a diagrammatic view of the end barring stitches.

Fig. 17 is a detail section thru the pivot of the lock lever.

Fig. 18 is a detail section taken thru the thread control device.

The improvements are shown in connection with a well known Singer button hole machine, and it will be necessary in the description to describe in detail many of the old parts to obtain a comprehensive understanding of the various improved mechanisms, their functions and time of cooperative operation.

1 indicates the base of the machine and 2 the arm rising therefrom. In the arm is mounted a drive shaft 3, connected in the

usual manner to operate the needle bar 4, and the lower stitch forming mechanism 4^a.

On the drive shaft is a beveled pinion 5, which meshes with a beveled pinion 6, which

operates the automatic end barring mechanism in the upper part of the arm. On the drive shaft is a worm 7, which engages a worm gear 8, mounted on a vertical shaft 9.

The worm gear 8 is provided with a sleeve and on the lower edge of same are ratchet teeth or serrations 10, which form a clutch member 11. Slidably mounted on the shaft 9, is a second clutch member 12, provided with ratchet teeth or serrations 13,

adapted at the proper time to engage the ratchet teeth 10. The clutch member 12 is provided with lateral slots 14, which engage extensions 15 formed in a flanged sleeve 16,

fixed to the vertical shaft 9, and interposed between the flange of this sleeve, and the clutch member 12, is a spring 17, normally causing the serrations of the clutch mem-

bers to engage, to impart motion from the drive shaft 3, to the vertical shaft 9. The

clutch member 12 is provided with an annular groove 18, and engaging therewith is a yoke 19, pivoted on a pin 20, on a frame 21, suitably supported in the vertical member of the arm 2. From the yoke extends a substantially vertical lever 22, so ar-

ranged as to be engaged by the end of a lever 23, commonly employed in the Singer button hole sewing machine to disconnect

the driving shaft from the vertical shaft to stop the feed motion when forming end

barring stitches. This lever is provided with a lug 24, with which the forked end

25 of a link 26, engages, the link being pivotally mounted on the end of a lever 27,

pivoted on the side of the arm, as usual in machines of this type. The lever 23, coop-

erates with automatic mechanism in the top of the arm under the plate 28, to so actuate

the mechanism to form end barring stitches. As this mechanism forms no part of the

present invention, except, it operates in sequence with my improvements, it is not

thought necessary to specifically illustrate or describe it in detail. It may be stated

however that the tension device 29, usually

released to free the upper thread after the

last purl stitch is formed is utilized in connection with my thread control.

On the lower end of the vertical shaft 9, is a pinion 30, which meshes with a gear

wheel 31, on a shaft 32. Also fast on the

shaft 32, just above the gear wheel 31 is a

cam disk 33, provided with two appropriately formed cam grooves 34 and 35. The

cam groove 34, acts to continuously reciprocate a work support 36, to feed the fabric, while the cam groove 35 acts, through appropriate connections to laterally move said work support.

Fast on the shaft 32, just below the horizontal member of the arm 2, is a double cam element 39 provided on its edges with two cams 40, each of which, in present known

machines terminate abruptly to produce a

sudden drop to shift the needle bar to form

the end barring stitches. In lieu of this

usual sudden termination of each cam, I

bevel off the ends, as at 41, so as to permit

a gradual, but steady drop of the end of the

lever 27 at the time the end barring stitches

are formed. It is to be understood that this

cam element is employed to shift the needle

bar and disconnect the clutch on shaft 9

twice in one revolution of the shaft 32, to

stop the feeding of the work during the formation of end barring stitches, as customary in button hole machines of the type shown.

The beveled portion 41 of each cam 40, is so arranged that between the time the end of the lever 27, commences to drop, until the time said lever reaches the full depth of the cam, several (say three or four, more or less) increased vibrations of the needle bar will

be made, and correspondingly short stitches of increasing length will be formed in the fabric. Then when the lever 27 reaches its full limit of movement, barring stitches of full length will be formed.

The only change or improvement in this feature of the machine resides in the shape of the cam portions. These, as stated have been altered so as to form several short 10 stitches, each succeeding stitch being slightly longer than the preceding one, as indicated at 42. Then the regular barring stitches 43, are formed directly over the short stitches, as shown diagrammatically in Fig. 16.

15 This results in producing two functions; First, if the needle is not properly timed to be out of the fabric when the increased vibration occurs to form an end bar, the drag is not sufficient to bend or break the needle, 20 nor is the movement of the needle sufficient to tear or drag the fabric. When the normal movement of the needle bar necessary to form full length barring stitches is divided, the increment of such movements becomes so 25 small that any drag of the needle, if such occurs, becomes wholly an immaterial factor, as the needle will flex without bending or breaking; Secondly, the piled up stitches produces a much stronger bar at the end of 30 the buttonhole. Of course this drag does not always occur, but when delicate parts and adjustments employed are considered, and the high speed the machine is run, any slight wear will change the timing, and invariably 35 this change will result in the needle not being withdrawn from the fabric when the shift of the bar takes place. This results, sooner or later, in the needle being caught, and as stated it is either broken or becomes 40 so distorted as to make it of no practical value, and another must be substituted.

45 Mounted in bearings on the base 1, is a transverse rock shaft 48, provided on one end with a handle 49, conveniently connected to be manually operated to rock the shaft forwardly or rearwardly. Extending rearwardly from the rock shaft is a trigger 50 adapted to engage a projection 51, on a rod 52 which extends through the base of the machine and 50 is connected in such way as to actuate the starting mechanism, when the handle is pulled in the direction of the arrow *a*. Also rising from the shaft 48, is a lever 54, provided with a lateral stud 55, designed to operate in a slot 56 in a lock lever 57. The lock lever 57 is pivoted at 58, to one side of the arm, and between the pivot pin and the arm is a friction coil 59, to create sufficient friction to hold the lock lever in any set position. 55 The slot 56 in the lock lever is elongated, the lower wall thereof is formed into a cam 60, with which the stud 55 is adapted to engage in the cycle of operation of the machine. The upper wall of the slot is provided

with an abutment 61, so disposed that when 65 the lock lever is depressed, the lateral lug 55 will encounter it, and the rock shaft 48 will be locked against forward movement.

Pivoted on one side of the arm 2, at 63, is a cutter actuating lever 64, provided at one 70 end with a slot 65, through which a stud 66, from a rod 67 extends. To the opposite end of the lever 64, is pivoted a link 68, provided at its upper end with a slot 69. The slot receives a stud 70, extending from the end of 75 a lever 71, pivoted to the arm, and extended into the head of the arm where it is suitably connected with the cutter bar to actuate the latter at the proper time.

At this point it may be well to point out 80 that a link 73 pivoted to the lock lever 57, at 74, extends upwardly and its upper hooked end 75 embraces the lever 71 to rock the lock lever when the cutting bar is actuated, to remove the abutment 61, from the path of the 85 stud 55.

Pivoted to the link 68 is a T-shape interponent 78, the upper end of the vertical member being provided with a flanged nose 79 which is adapted to engage under the 90 stud 70, once during the cycle of stitching and cutting, if the machine be correctly timed to perform its functions in proper sequence. The outer end of the horizontal member 80, of the interponent is normally 95 supported on the nose 81, of a bell crank lever 82, pivoted to a bracket 83. The opposite end of the bell crank lever is provided with a depending roller 85, which lies in the path of a cam 86, fixed on the vertical shaft 100 32, and timed to rock the bell crank lever to withdraw the nose 81 from under the member 80 of the interponent at about the time the cutting bar is to be operated, which permits a spring 87, to rock the interponent 105 on its pivot, and present the flanged nose 79, under the stud 70.

On a pin extending from the end of the member 80, of the interponent, is mounted the end of an operating rod 90, conveniently 110 bent around the link and interponent to position its vertical portion adjacent a thread control means about to be described.

As previously stated the usual tension device 29 on top of the arm is employed, and adjacent thereto is a post 92, on which is loosely supported a friction lever 93, and a yoke 94. The yoke is extended from the post and its end is bent upwardly at 95, and the outer member of the yoke is curved 120 beyond the post and lies over the friction lever 93. A light spring 96 is connected to the friction lever between the legs of the yoke, and its opposite end is attached to the bent up end 95, of the yoke. The tension and disposition of the spring is such as to draw the friction lever up against the underside of the curved leg of the yoke, 125

and against a stop pin 98, depending from the leg.

The yoke, hence the friction lever are adjustably supported on the post by a set 5 screw 99, to permit of a limited radial adjustment of the end of the friction lever to determine the length of thread to be drawn out under tension, this of course being determined by the number of stitches employed in the last bar, for it is to be understood that the thread tension is brought into play to perform its function at this particular time in the cycle of operation to control the buttonhole cutting blade.

15 Located on top of the arm 2, between the post 92, and the rod 90 is a block 100, provided on its forward end with a reduced extension 101, formed with a thread guide opening 102. At the rear end of the block 20 is a vertical pin 103, substantially in alignment with the opening 102 and between the latter and the pin, the block is provided with a vertical opening 104. The outer end of the friction lever 93 is flared and thinned, 25 and operates over the opening 104, but the spring 96 normally holds the flared end slightly spaced from the upper surface of the block to allow free passage of the thread when the tension control is inactive, as best 30 shown in Fig. 18.

On the upper end of the rod 90 is secured a cross head 105, and depending from the opposite end is a pin 106 which is disposed above and in alignment with the opening 104. The lower end of the pin terminates 35 above the flared end of the friction lever the two just about touching when the parts are in normal position.

The thread comes from a suitable source 40 of supply, thence passes over a tension check, 106^a, and through the tension device 29, and around the pin 103, and over the upper surface of the block, and then down through the opening 102. From the block 45 100, the thread is directed over another check 108, on the arm of the machine, and is then led to a tension device 109, through a spring guide 110, under a fixed hook guide 111, and thence upwardly through an eye 50 in the take up lever 112^a, then downwardly through a guide slot 113^a, to the eye of the needle.

In the cycle of operation of the machine, 55 the latch 82 is released a short time before the cutter is to be operated and the interponent 78 is rocked slightly by the spring 87, until the end of the pin 106, presses the flared end of the friction lever 93, against the tension of spring 96, and the thread is 60 frictionally engaged on the surface of the block 100, and thereby the thread is again tensioned at the time the last set of barring stitches is formed. This action causes the stitches to be sewed in tight to strengthen 65 the buttonhole, and tie in the thread. As

the barring stitches are formed the friction lever 93, by reason of the forward movement of the thread is moved step by step from under the pin 106, and before the last 70 stitch is made, the parts are so timed that the rear edge of the flared end of the friction lever frees the pin 106, and promptly the spring 87, rocks the interponent 78, and the rod 90, and cross head 105 drop, the pin 75 falling into the opening 104 and the nose 79, coming into position under the stud 70. The parts are now in position to cause actuation of the cutter bar when lever 64 is 80 rocked by depression of rod 67 by cam 126 to form the cut between the stitches in the fabric to complete the button hole.

For further reference it may be stated that when lever 71 is rocked it exerts an upward pull on the hook of the link 73, and rocks the lock lever 57 upwardly which 85 positions the abutment 61, above the path of movement of the stud 55, to permit the operator to subsequently lift the clamp, etc.

Let it be supposed that the needle thread breaks, or for some reason becomes slack, 90 or the lower thread pays out and the upper thread fails to properly stitch, then it is, that the automatic thread tension control performs its function to prevent the cutter bar operating and damaging the fabric, and 95 prevents manual lifting of the clamp.

If the thread in front of the block 100, be slack, when the latch lever 82, is tripped as it will be near the end of the stitching operation, and the pin 106 drops on the friction 100 lever 93, even though the stitching mechanism is still operating to form the last of the end bar stitches, no movement will be imparted to said friction lever 93. Therefore the rod 90 will be held suspended, and 105 the nose 79, of the interponent 78, cannot get under the stud 70.

The result is that when the lever 64, is rocked, the slot 69, permits the link 68 to ride on the stud 70, and no movement will 110 be imparted to the cutting bar. Since the abutment 61, on the lock lever 57 is now in the path of the stud 55, the operator, even if she has overlooked the fact that the cutter bar has not been operated, cannot lift the 115 clamp, as the action is locked.

The trouble with the thread can be cured, and the stitching mechanism, is again started and the same defective stitching is worked over, and when completed the cutter 120 operates to make the slit. It will therefore be seen that the tension of the thread not only controls the action of the cutter, but it also controls the clamp.

Reverting to the transverse shaft 48, it 125 has secured thereon, adjacent the operating handle 49, a forwardly projecting block 112, bifurcated at its front end to receive a roller 113 to engage the tail piece 114, of a work clamp 115, and on its side is a cam 116. This 130

cam cooperates with a cam surface 117, on a lever 118, on a longitudinal shaft 119, mounted in bearings on the arm. Depending from the shaft 119, is a projection 120, 5 which at the proper time cooperates with an extension 121, projecting rearwardly from the transverse shaft 48. From the rear end of the shaft 119, extend a lever 122, and on the end of same is a pin 123, normally 10 supported on a flange of the stop and start mechanism, the lever being drawn down by a spring 124, when the stitching mechanism is thrown into connection with the power.

The stop motion and starting mechanism 15 as shown, are the same as that now in use, except that specific additions have been made to render the time of operation sure and effective. As is well known when the trip rod 52, is depressed, the stop and start mechanism 20 is rocked forwardly on pivots 125, to shift the belt from the loose to the fast pulley, and that when the stitching operation is completed, this movement is reversed, and momentum is largely depended upon to rotate a cam 126, to depress the rod 67, which 25 operates the cutter bar. Due to this latter fact the movement of the cutter bar does not always get the proper momentum, which results in the blade remaining in the fabric, 30 and in subsequent operations in the cycle of movement of the machine, the blade becomes bent or broken.

In the present improvement I take advantage of the present construction, and the 35 movements incident thereto, and arrange means which absolutely insures of the parts being released from the influence of the power at a definite point in its rotation, notwithstanding the fact that the primary automatic locking and releasing mechanism has 40 been tripped and the connection has been unlocked.

On an extension 127, of the stop and start mechanism frame 128, is fastened a stud 45 129, of a belt guide 130, and secured on the stud is a guide member 131, having a horizontal overhanging portion 132, which lies over the upper end of the extension 127. The forward end of the horizontal over- 50 hanging portion 132, is provided with spaced ears and passing therethrough is a substantially right angular trip 134. The leg of the trip which passes through the extension is cut away to form a catch 135, which 55 is normally held in a vertical position by a spring 136.

Pivoted on the side of the arm is a lever 137, the rear end of same being cut away to form a latch 138 to engage the catch 135. 60 This arrangement composes what I term the secondary locking and releasing mechanism.

When the frame 128, of the stop and start mechanism is thrown forward to operate 65 the stitching mechanism, the parts are held

by primary automatic locking means 139, located under the base of the machine, such means being substantially the same as the construction disclosed in the patent to Allen No. 743213, dated November 3, 1903. When 70 in this position the catch 135, is slightly in advance of the latch 138, a very slight distance as shown in Fig. 14, and the trip is just out of the path of movement of the cam 126, a corresponding distance. During 75 the time the stitching mechanism is performing its usual function, the relationship between the catch and latch, and between the end 134 of the trip and the cam remain the same. When the stitching operation is 80 completed, the primary releasing means 139, is actuated, and the frame of the stop and start mechanism is free to be uncoupled, and moves the short distance (indicated at 141) between the latch and the catch of the secondary locking and releasing mechanism, and is momentarily held. This action positions the end 134, of the trip in the path of movement of the nose 143 of the cam 126. In this interval the power means still rotates the driving shaft and continues so until 85 the cam 126 strikes the trip 134. When this occurs, the leg of the trip is turned in the ears of the block and the cutout portion or catch is turned horizontally, and the 90 flange of the latch 138 is released and the frame returns to normal position and the belt is shifted to the loose pulley in the customary manner.

By this means, every time the cutter bar 95 is operated by the cam 143 the point of release of the power is identically the same in each cycle of operation of the machine which results in accurate timing and the imparting of a definite stroke to the bar which insures of the blade cutting the fabric and withdrawing a definite distance to remove it from the path of the trimmers.

The secondary locking and releasing means also properly times the movement to insure sufficient momentum to bring the flat face of the nose of the cam 126 against the rod 67, to permit the end of the latter to engage its seat.

As an additional safety means to prevent 110 lifting the clamp 115 or operation of trimmers if the stop and start mechanism should fail to assume its normal position, the projection 120 on the longitudinal shaft 119 is so disposed, with reference to the extension 121, on the transverse shaft 48, as to preclude 115 rocking of the handle 49. That is to say, if per chance the frame 128, did not settle back to its exact normal position, the lever 122 would not assume its normal elevated position. Consequently the longitudinal shaft 119, will not be rotated to its normal position and the lower end of the projection 120 would lie in the path of the extension 121. If the operator should at- 120 125 130

tempt to rock the transverse shaft 48, forwardly in direction of arrow *b*, obviously she would find it locked. Therefore neither the clamp can be raised, nor the trimmers 5 operated until the frame 128 is in its proper position.

The clamp and the trimmers are operated in substantially the same manner as described in my copending application for patent filed Sept. 15, 1917, Serial No. 191,573, and therefore but a brief description of the 10 operation will be here given.

The clamp 115, is conventionally illustrated and is adapted to be manually raised 15 or lowered to insert or remove the fabric. It is provided with the tail piece 114 which lies under the roller 113, and when the operator rocks the shaft in direction of the arrow *b*, the tail piece is depressed and the 20 clamp is elevated. Before this action takes place, the cam 116, engages the cam surface 117 on the lever 118 which rocks the latter, and through appropriate connections 160, under the base 1, the lower trimmer 161, 25 is operated to sever the lower thread. The upper thread trimming mechanism 162, is in the mean time automatically operated by the arm 163 on the shaft 119.

The operation of the various parts has 30 been given somewhat in detail, but it is believed a brief general description of the sequence of operations of a complete cycle of movement of the machine will impart a more comprehensive understanding of the 35 invention.

Assume the parts are in the position of rest as shown in Figs. 1, 2 and 3, and it is desired to form a buttonhole. The operator 40 pulls the handle 49, to rock the shaft 48, in direction of the arrow *A*, which causes the stud 55 to engage the cam 60, of the lock lever 57, and thereby present the abutment 61, in the reverse path of movement of said stud, and at or about the time this movement 45 occurs the trigger 50, engages the projection 51, and the primary locking and releasing mechanism is actuated and the starting mechanism is thrown into operation. This action also sets the secondary locking 50 and releasing mechanism.

The work support carrying the fabric is continuously moved toward the rear to form a row of purl stitches and is stopped, and the end barring stitches are formed, and then 55 the work is laterally shifted, and the movement of the work support is reversed and the other purl stitches are formed. The movement of the work support is again stopped and the second end barring stitches 60 are formed, and the work support is again laterally shifted, and moved rearwardly a short distance and a few additional side stitches are formed due to the primary and secondary lock and releasing devices.

65 When forming the second end barring

stitches the latch 82, is automatically operated and the interponent 78, is released momentarily but is promptly held by the pin 106, falling on the lever 93, which places the thread on the block 100, under tension. As 70 the thread for the second barring stitches is pulled, the lever 93, is frictionally operated or moved step by step, and immediately the opening 104, is uncovered, the pin falls, which permits the interponent to assume position 75 to operate the cutter. The stitching operation having been completed, the primary lock and releasing means is tripped, and the frame 128, is permitted to move back slightly but it is caught by the secondary 80 lock and releasing means and is momentarily held until the nose 143, of the cam strikes the end, of the trip 134, which permits the stop motion to come into play. In the meantime the cutter bar is operated, and the lever 85 71, lifts the hooked connection 73, and restores the lock lever 57, to its normal position. Of course, when the longitudinal shaft 119, is returned to its position of rest the upper trimming mechanism is automatically 90 actuated to trim the upper thread.

The operator now reverses the movement of the handle 49, in direction of arrow *B*, and the lever 118, is operated to trim the lower thread, and subsequently the roller 95 113, engages the tail piece 114, and the clamp is raised. This brief cycle of operation occurs if the parts are properly timed, and the stitches are properly formed. Suppose, however, that the upper thread is slack or 100 breaks, or the bobbin thread plays out, or stitches are skipped, or something occurs to prevent return of the parts to proper position, then it is that the various improvements described perform their respective functions. 105

If something is wrong with either the upper or lower thread, tension on the upper thread is immediately relaxed, consequently when the pin 106, falls on the lever 93, the latter remains stationary, and therefore the 110 interponent cannot assume position to cause actuation of the cutter bar. Hence the lock lever 57, is not lifted which leaves the abutment 61, in the path of the stud 55. If the operator should attempt to rock the shaft 48, 115 in direction of the arrow *B*, to trim the lower thread and lift the clamp, she will find the parts locked. The trouble with the thread is cured, and the handle is again operated in direction of the arrow *A*, and the stitching 120 operation is repeated on the same piece of fabric, originally clamped. If the second operation produces properly formed stitches the operator can now rock the shaft 48, in direction of arrow *B*, as the lock lever 57, 125 was rocked upwardly far enough to remove the abutment 61, from the path of movement of the stud 55. This, of course, permits of the trimming of the lower thread and the lifting of the clamp.

Now let it be assumed that the stitching was properly formed, but the frame 128, and the parts co-operating therewith failed to come back to proper position. Then the projection 120, lies in the path of the extension 121, which prevents the operator rocking shaft 48, to trim the lower thread and lifting the clamp if the stitches were improperly formed and the cutter blade was operated 10 and severed the fabric it would ruin it, and then when the clamp is raised and the fabric removed it is either impractical, or too expensive to repair the stitches but by the thread control this is obviated. The thread 15 control not only prevents operation of the cutter blade, but it prevents lifting the clamp, so that the fabric is saved and can readily be stitched, where originally clamped and gaged. So also with the safety device 20 for preventing operation of the clamp, if the stop motion fails to properly seat. Were it not for this device, great damage might result to the blade when trimming, if the blade failed to assume normal position.

25 Too much importance cannot be placed on the formation of the cams to permit gradually increased vibration to the needle bar when changing from position when forming purl stitches, to position for forming end barring stitches. This arrangement not only saves the needle, but it also saves tearing and pulling of the fabric.

What I claim is:—

30 1. In combination, a buttonhole machine, including a buttonhole cutting blade, means for operating the cutting blade, including an interponent, and a device operated to be moved by the normal feed of the thread for releasing the interponent to operate the cutter blade when stitches are properly formed.

40 2. In combination, a buttonhole machine, including a buttonhole cutting blade, means for automatically operating the cutting blade, a normally disconnected interponent, and means released when the thread is properly fed to set the interponent to permit the cutter operating means to actuate the cutting blade when stitches are properly formed.

50 3. In combination, a buttonhole machine including a buttonhole cutting blade, means for operating the cutting blade, including an interponent, means for holding the interponent in inoperative position, and means actuated by the thread when same is under proper feed and tension and being pulled off to form stitches to release the means which holds the interponent, whereby to permit the cutting blade operating means to actuate said cutting blade.

60 4. In combination, a buttonhole machine, including a buttonhole cutting blade, means for operating the cutting blade, and means operated to be moved by the tension and feed of the thread for permitting the nor-

70 mal actuation of the cutting blade, said means becoming inactive and preventing operation of the cutting blade if the thread becomes slack through imperfectly formed stitches or if the thread breaks.

5 5. In combination, a buttonhole machine, including a buttonhole cutting blade, means for operating the cutting blade, and means actuated to be moved by the thread when under tension and feed to permit the operating means to actuate the cutting blade when the thread is properly tensioned.

75 6. In combination, a buttonhole machine, including a buttonhole cutting blade and operating means therefor, said operating means including a device which is actuated to be moved by the feeding of the thread when said thread is under tension, to permit the operation of the cutting blade and is rendered inactive when the thread breaks 80 or becomes slack to prevent operation of the cutting blade.

80 7. In combination, a buttonhole machine, including a buttonhole cutting blade and operating mechanism therefor, and means made active by the normal stitching in of the thread at a predetermined time during the stitching operation to permit the operating means to actuate the cutting blade, said means being rendered inactive when 95 the thread is slack or breaks so as to prevent operation of said cutting blade.

85 8. In combination, a buttonhole machine, including upper and lower stitch forming mechanism and a buttonhole cutting blade, 100 means for operating the cutting blade, and a device rendered active only when the upper thread is properly sewed in to permit operation of the cutting blade, said device remaining inactive if either the upper or 105 lower thread breaks or plays out, or the stitches skip and the thread becomes slack and thereby prevents operation of the cutting blade.

90 9. In combination, a buttonhole machine, including a buttonhole cutting blade and means for operating same, a work clamp, means for operating the work clamp, and a device actuated only when the tension and sewing in of the thread is normal to permit actuation of the cutting blade and the work clamp, said device when inactive due to slack or broken thread preventing actuation of the cutting blade and work clamp.

10 10. In combination, a buttonhole machine, including a buttonhole cutting blade and means for operating same, a work clamp, a member to start the buttonhole machine and to operate the work clamp, a locking lever, and a device actuated only when the tension 120 and feed of the thread is normal to permit operation of the cutting blade and positioning the locking lever to permit raising the work clamp, said device being inactive if the thread becomes broken or slack and 125 130

thereby preventing operation of the cutting blade and operation of the work clamp.

11. In combination, a buttonhole machine including a buttonhole cutting blade, means for operating same including an interponent, and a member operable with the interponent, a device associated with the member and which lies adjacent the thread but normally unaffected thereby, and an automatically actuated trip to release the interponent which permits the member to engage the device associated therewith to cause the latter to contact with the thread and be moved by said thread to permit the interponent to actuate the cutting blade, the said device being inactive if the thread breaks or becomes slack and thereby prevents operation of the cutting blade.
12. In combination, a buttonhole machine including a buttonhole cutting blade, and means for operating same, said means including an automatically tripped interponent, a thread control device operatively associated with the interponent and comprising a thread guide, a spring held thread engaging element normally spaced from the thread guide to permit free passage of the thread, and a connection between the thread engaging element and the interponent to cause said element to engage the thread on the thread guide when the interponent is tripped, whereby the tension of the thread actuates the element to permit the interponent to be positioned to cause actuation of the cutting blade.

13. A button hole machine, including a buttonhole cutting blade, means for operating same including an interponent, a thread control device comprising an element normally held out of engagement with the thread, a device between the element and the interponent, and means for adjusting the position of the element with reference to the device to determine the duration of time the element operates, the device when the interponent is tripped causing the element to engage the thread which actuates said element if the tension of the thread is normal to permit operation of the cutting bar, the element remaining inactive if the thread breaks or becomes slack.

14. In combination, a buttonhole machine comprising a buttonhole cutting bar and a work clamp, a thread controlled device actuated only when the thread is under normal tension and sewing in and means actuated by the thread control device to permit operation of the cutting blade and the work clamp, the thread control device remaining inactive if the thread breaks or becomes slack, thereby preventing operation of cutting blade and the work clamp.

15. In combination, a buttonhole machine including a work clamp and a starting element, a locking lever between the starting

element and the work clamp, and a thread control which when the thread is being moved and sewed in under normal tension actuates the locking lever and permits of the starting element being moved to raise the work clamp, but which when the thread is slack or breaks remains inactive and leaves the locking lever in position to prevent raising of the work clamp.

16. In combination, a buttonhole machine, including a buttonhole cutting blade and a work clamp, a starting element, a stud carried by the starting element, a locking lever having an abutment and a cam with which the stud cooperates to set said lever in locking position, and a thread control device operated only when the thread is being sewed in and connections between the cutting blade, locking lever and the thread control device, whereby when the thread breaks or becomes slack the thread control device remains inactive and the clamp is locked and the cutting blade is rendered inactive.

17. A buttonhole machine comprising stitching mechanism, a buttonhole cutting blade, thread feeding devices, including an element automatically brought into operative position to engage the thread by the cutting blade controlling mechanism and subsequently moved step by step only when the thread is properly sewed in, whereby to permit operation of the cutting blade.

18. A buttonhole machine comprising upper and lower stitch forming mechanism, a buttonhole cutting blade, thread controlling devices including an element automatically brought into operative position to engage the upper thread by the cutting blade actuating mechanism and moved step by step only when the upper and lower threads are properly tensioned, whereby to permit operation of the cutting blade.

19. A buttonhole machine comprising stitch forming mechanism, a buttonhole cutting blade, means to cause the stitch forming mechanism to form predetermined side and end barring stitches and stop, thread actuated devices including an element automatically brought into operative position to engage the thread by the cutting blade controlling mechanism at or about the time the last end barring stitches are to be formed and moved step by step only when the upper thread is under normal tension, whereby to increase the tension on the thread and permit operation of the cutting blade.

20. A buttonhole machine, comprising stitch forming mechanism, a cutting blade, stop and start mechanism, a cam for actuating the cutting blade, primary releasing means to actuate the stop mechanism, and a secondary releasing means brought into operative position when the primary releasing means is tripped, whereby to insure of the cam operating on the cutting blade actuating

means at the same predetermined point in every cycle of operation of the machine.

21. A buttonhole machine, comprising stitch forming mechanism, a cutting blade, 5 stop and start mechanism, a cam for actuating the cutting blade, primary releasing means to actuate the stop mechanism, and a secondary releasing means brought into operative position when the primary releasing means is tripped, to hold said stop mechanism to be subsequently tripped when the cam reaches a predetermined point in its rotary motion to insure of the cutting blade actuating mechanism being actuated 10 at the same definite point in each cycle of operation of the machine.

22. A buttonhole machine, comprising stitch forming mechanism, a cutting blade, stop and start mechanism, primary releasing 20 means to release the stop mechanism after the predetermined stitching operation is completed, a cam to operate the cutting blade, secondary releasing means, including a latch and a trip, the trip being moved with 25 the stop and start mechanism and adapted to be positioned for operation to release the latch when the primary releasing means releases the stop mechanism, whereby to insure of the cam actuating the cutting blade actuating mechanism at the same predetermined 30 point in each cycle of operation of the machine.

23. A buttonhole machine, comprising stitching forming mechanism, a cutting 35 blade, stop and start mechanism, a cam to actuate the cutting blade, secondary releasing means comprising a trip carried by the stop and start mechanism and a latch positioned to cooperate with the trip when the 40 stop and start mechanism is operated in one direction, primary releasing means to release the stop and start mechanism when predetermined stitches have been formed, the latch momentarily holding the stop 45 mechanism and positioning the trip after being released by the primary releasing mechanism, whereby when the trip is actuated the cam actuates the cutting blade with the same momentum in every cycle of operation 50 of the machine.

24. A buttonhole machine, comprising a stitch forming mechanism, a cutting blade, a cam for actuating the cutting blade, stop and start mechanism, a work clamp, primary 55 releasing means to release the stop and start mechanism, secondary releasing means which is set when the stop and start mechanism is operated in one direction, and which momentarily holds the stop and start mechanism in its reverse movement when the primary releasing means is actuated, and which subsequently releases the stop and start mechanism when the cam reaches a predetermined point, and means under control of 60 the stop and start mechanism for preventing 65

raising of the work clamp if the parts fail to assume normal position.

25. A buttonhole machine comprising stitch forming mechanism, means associated therewith to form a predetermined number 70 of stitches and stop, a cutting blade, and means operable by the tension and feed of the thread when certain of said stitches are formed to permit operation of the cutting blade if the predetermined number of 75 stitches have been properly formed up to the time of operation of said cutting blade.

26. A buttonhole machine comprising stitch forming mechanism, means associated therewith to cause said stitch forming 80 mechanism to complete one cycle of operation and stop, a work clamp, a cutting blade and means operable by the thread only during a definite period of the cycle of operation of the cutting blade and permit lifting of 85 the clamp.

27. A buttonhole machine comprising stitch forming mechanism, means associated therewith to cause the stitch forming mechanism to form side and end barring stitches, 90 and thread tensioning means operative only at or about the time the last end bar stitches are being formed.

28. A buttonhole machine comprising stitch forming mechanism, means associated 95 therewith to cause the stitch forming mechanism to form side and end barring stitches, and thread tensioning means operative only at or about the time the last end bar stitches are being formed, and then only if the preceding 100 stitches be properly formed.

29. A buttonhole machine comprising stitch forming mechanism, means associated therewith to cause the stitch forming mechanism to form side and end barring stitches, 105 a cutting blade, thread tensioning means operative only at or about the time the last end bar stitches are being formed to cause the end bar stitches to be worked in under tension and permit operation of the cutting 110 blade.

30. A buttonhole machine comprising stitch forming mechanism, means associated therewith to cause the stitch forming mechanism to form side and end barring stitches, 115 a cutting blade, a work clamp, and thread tensioning means operative only at or about the time the last end bar stitches are being formed to cause the end bar stitches to be worked in under tension and permit operation of the cutting blade, and permit lifting of the work clamp.

31. A buttonhole machine comprising stitch forming mechanism, a cutting blade, a work clamp, and means under control of 125 the tension and feed of the thread for permitting operation of the cutting blade and lifting of the clamp if the stitches be properly formed, said means being operable only by the thread when certain predetermined 130

stitches are formed and then only if the stitches be properly formed, and means between the cutting blade and the work clamp to actuate the work clamp releasing mechanism during the operation of the cutting blade.

32. A buttonhole machine comprising stitch forming mechanism, a work clamp, a cutting blade, actuating mechanism between 10 the work clamp and the cutting blade, including a latch and a resetting link, means connected to the actuating mechanism and operated only by the thread when under tension and the stitches are properly formed, 15 whereby the cutting bar may operate and actuate the link and set the latch to permit of the work clamp being raised.

33. A buttonhole machine comprising stitch forming mechanism, a cutting blade, 20 a work clamp, and means only operated during a portion of the stitching operation by the tension and feed of the thread to permit operation of the cutting blade and lifting of the work clamp.

34. A buttonhole machine comprising stitch forming mechanism, means associated therewith to cause the stitch forming mechanism to form side and end barring stitches, and thread tensioning means operative only 30 at the time certain of the end barring stitches are being formed.

35. A buttonhole machine comprising stitch forming mechanism, and thread tension means controlled at a predetermined 35 time in a stitching operation by the tension and feed of the thread.

36. A buttonhole machine comprising stitch forming mechanism, and thread tension means brought into operation only at a 40 predetermined time in a stitching operation and controlled by the tension and feed of the thread, but inoperative if the thread tension slackens.

37. A buttonhole machine comprising 45 stitch forming mechanism, a main thread tensioning means, means for automatically releasing said main tensioning means, and means subsequently operated to further apply tension on said thread while stitching, 50 said means being controlled by the tension and feed of the thread.

38. A buttonhole machine comprising 55 stitch forming mechanism, a main thread tensioning means, means for automatically releasing said main tensioning means, and means subsequently operated to further apply tension on said thread while stitching, said means being controlled by the tension and feed of the thread and released from 60 said control only if the stitches be properly formed.

39. A buttonhole machine comprising 65 stitch forming mechanism, a work clamp, main thread tensioning means, automatic means for releasing said main thread ten-

sioning means, other means to subsequently apply tension to said thread, said other means being controlled by the tension and the feed of the thread, and mechanism between said latter means and the work clamp 70 to permit lifting of the latter only when said subsequent tension is applied.

40. A buttonhole machine comprising 75 stitch forming mechanism, a work clamp, a buttonhole cutting blade, main thread tensioning means, automatic means for releasing said thread tensioning means, other means to subsequently apply tension to said thread, said other means being controlled by the tension and feed of the thread, and mechanism between said latter means and the work clamp and the buttonhole cutting 80 blade to permit lifting of said clamp and operation of said cutting blade only when the 85 stitches are properly formed.

41. A buttonhole machine comprising automatic mechanism for forming purl stitches and end bar stitches of different lengths, automatic thread tensioning mechanism operated to tension the thread at the time the 90 purl stitches are formed, and other thread tensioning means brought into operation when certain of the end bar stitches are formed, said other thread tensioning means being controlled by the tension and feed of 95 the thread, said last mentioned tension means being released only when the stitches are properly formed.

42. A buttonhole machine comprising 100 automatic mechanism for forming purl stitches and end bar stitches of different lengths, a buttonhole cutting blade, automatic thread tensioning mechanism operated when the purl stitches are formed, other thread tensioning mechanism brought into operation 105 when certain of the end bar stitches are formed, said other thread tensioning means being controlled by the tension and feed of the thread, and mechanism between the last mentioned tensioning means and the buttonhole cutting blade to permit operation of the latter, only when the stitches are properly 110 formed.

43. A buttonhole machine comprising 115 stitch forming mechanism, a buttonhole cutting blade, thread tensioning means operated and controlled by the tension and feed of the thread only when the stitches are properly formed, and means between said thread tensioning means and the buttonhole 120 cutting blade to prevent operation of the latter, if the stitches are not properly formed.

44. A buttonhole machine comprising 125 stitch forming mechanism, a work clamp, thread tensioning means operated and controlled by the tension and feed of the thread only when the stitches are properly formed, and means between said thread tensioning means and the work clamp to prevent lifting 130

of the latter if the stitches are not properly formed.

45. A buttonhole machine comprising stitch forming mechanism, automatic means 5 cooperating with the said stitch forming mechanism to form main purl and end bar stitches and several additional purl stitches after the last end bar stitches, a cutting blade, automatic tensioning means operable 10 to tension the thread while the main purl stitches are being formed, other thread tensioning means controlled by the tension and feed of the thread only at the time the last end bar and additional purl stitches are being formed, and means between said other 15 thread tensioning means and the cutting blade to permit operation of the latter only when the stitches are properly formed.

46. In a stitching machine adapted to 20 form a group of stitches comprising upper stitch forming mechanism, lower cooperating stitch forming mechanism, lifting means, means for normally tensioning the thread during the stitch forming operation, other thread tensioning means controlled by 25 the normal tension and feed of the thread when stitches are properly formed by the stitch forming mechanism, a cloth clamp,

means controlling the second mentioned tensioning means, tripping means to actuate 30 the lifting means when the stitches are properly tensioned and placed.

47. A stitching machine comprising stitch forming mechanism, a work clamp, normal thread tensioning means, other thread tensioning means operated and controlled by 35 the tension and feed of the thread only when the stitches are properly formed, said other tensioning means permitting of the raising of the work clamp only when the said 40 stitches are properly tensioned and placed.

48. A buttonhole machine comprising stitch forming mechanism, a work clamp, a buttonhole cutting blade, thread trimming mechanism, thread tensioning means operated and controlled by the tension and feed 45 of the thread only when the stitches are properly formed, and means between the said thread tensioning means and the buttonhole cutting blade and thread trimming 50 mechanism to prevent the operation of said buttonhole cutting blade and said thread trimming mechanism if the stitches are not properly formed.

In testimony whereof I affix my signature. 55
HENRY C. MILLER.
